DESIGN FOR A MOCCASIN

Edward W. Shaffer, Wichita, Kans.

Application August 21, 1946, Serial No. 132,700

Term of patent 14 years

(Cl. D7—7)

To all whom it may concern:

Be it known that I, Edward W. Shaffer, a citizen of the United States, residing at Wichita, in the county of Sedgwick and State of Kansas, have invented a new, original, and ornamental Design for a Moccasin, of which the following is a specification, reference being had to the accompanying drawing, forming a part thereof.

Fig. 1 is a top plan view of the moccasin, showing my new design in the collapsed condition.

Fig. 2 is a front perspective view of the moccasin in the normal condition ready for application to the foot; and

Fig. 3 is a rear perspective view of the disclosure in Fig. 2.

I claim:

The ornamental design for a moccasin, as shown and described.

EDWARD W. SHAFFER.
